FUEL-INJECTION APPARATUS FOR INTERNAL-COMBUSTION ENGINES AND LIKE PURPOSES

George Amery, Harborne, Birmingham 17, England, assignor to Amery Holdings Limited, Oldbury, Birmingham, England, a British company

Application April 19, 1943, Serial No. 483,652
In Great Britain February 17, 1942

6 Claims. (Cl. 137—144)

This invention comprises improvements in or relating to fuel-injection apparatus for internal-combustion engines.

According to the present invention a fuel-control valve comprises a valve-body, an inlet thereto, a plunger therein having a duct extending through it from one end open to the inlet toward a seating at the other end, an obturating-member movable toward the plunger to bear on the seating and thereby close the duct against the flow of fuel through the duct, a piston face on the obturating-member exposed to inlet fuel-pressure to urge it open and control means independent of the fuel-pressure, controlled by the valve, to close the obturating-member against said pressure, whereby seating and unseating of the obturating-member is effected to close and open the valve, the plunger and seating thereon being free to move with the obturating-member for a short distance in the closing direction after the valve is closed.

The invention includes an injector or distributor having a fuel-control valve as above set forth wherein an expansion chamber is provided between the plunger and an annular shoulder or abutment engaging therewith, which chamber is in communication with the fuel-nozzle of the injector and on the relative movement which occurs between the shoulder and plunger when the plunger and obturating-member move together after the valve is closed serves to relieve fuel-pressure at the nozzle for the purpose of ensuring a rapid cessation of injection when the valve is closed.

The fuel-control valve may be employed to control the admission of fuel to a needle-valve seating for the injector or distributor and the closing means for the needle-valve or plunger or obturating means, as the case may be, may be assisted, if desired, by spring action, although in certain forms according to the invention the employment of springs may be obviated.

The preferred arrangement according to this invention leads to an exceptionally rapid fall of fuel-pressure when obturation occurs but not before.

Referring now to the accompanying drawing—

Figure 1 illustrates in longitudinal section a fuel-injection device for an internal-combustion engine, while

Figure 2 illustrates a cross-section through the line II—II in Figure 1.

Figure 3 illustrates in cross-section a modification.

Figure 4 is a diagram of the essential parts of the valve as illustrated in Figure 3.

The invention will now be described, by way of example, as applied, more particularly to the arrangement described and illustrated with reference to Figures 4 and 5 of my United States Patent No. 2,053,311, granted September 8, 1936, wherein a number of injectors are operated from a single fuel supply system. A pipe connection with this system is made directly to each injector for injection purposes and a branch from this pipe connection is led by way of a mechanically-actuated valve to each injector. This mechanically-actuated valve controls the operation of the injector associated therewith so that at the moment when injection is to commence the valve cuts off the piston closing-means from communication with the supply system and places the chamber containing the piston closing-means in connection with the atmosphere or with a drain pipe, while at the moment when injection is to be cut off the valve places the piston closing-means in the injector in communication with the supply system.

The inlet pipe 11, Figure 1, leads fuel from the fuel pressure system to the injector 12. The body 13 of the injector is tubular and its upper end is formed with an internal screwthread 14. With the screwthread 14 engages a nut 15 which has an annular projection 16 at its inner end. The annular projection 16 engages with a shoulder 17 on the inlet pipe 11 and forms a fluid-tight joint, when the nut 15 is screwed hard up, between the conical end 18 of the pipe 11 and the correspondingly shaped recess 19 in a guide member 20 fixed in the bore 21 of the body 13 of the injector 12.

The guide member 20 is formed with a central bore 22 in which a free plunger 23 is slidable, the upper end of the bore 22 opening into the recess 19. The plunger 23 is provided with a central duct 24 and the lower end of this plunger is integral with a piston 25 arranged in a chamber 26. The lower end of the chamber 26 is formed by the upper end wall of a constriction 28 arranged between this chamber and a chamber 29, the lower wall of the chamber 26 being formed with an annular projection 30 concentric with this chamber. The constriction 28 has a central bore 31 in which a plunger 32 is slid able, the upper end face of this plunger being adapted to seal or act as an obturating-member for the lower end of the duct 27 of the piston 25 when these parts are in contact with each other. A duct 33 extends between the lower end of

the chamber 26 and the upper end of the chamber 29, the upper end of this duct opening from the face of the annular projection 30 into the former chamber.

A bore 34 extends from the chamber 29 to the lower end of the injector body 13. The bore 34 is divided into two control-chambers 35 and 36 by the member 37 which is fixed in position by the means of a grub screw 38. A duct 39 of the member 37 interconnects the control-chambers 35 and 36, and this duct is connected by a duct 40 with a control-pipe 41 from the mechanically-actuated valve above described which acts as a distributor. The control-pipe 41 is formed with a conical end 42 which fits into the correspondingly shaped part of the duct 40. The end 42 of the pipe 41 is pressed into fluid-tight contact with the conical wall of the duct 40 by the annular projection 43 on the end of a nut 44, the screw of which engages with the internal screwthread 45 of the nipple 46 formed on the body 13 of the injector, when the nut 44 is tightened up.

In the control-chamber 35 is disposed a control-piston 47 which actuates the plunger 32. It will be noted that the area of control-piston 47 is somewhat greater than that of plunger 23 to ensure that it can lift the plunger against fuel-pressure in pipe 11. In the chamber 36 is mounted a piston 48 which is connected to, or formed integrally with, the stem 49 of a needle valve which seats in a nozzle 52. The needle valve 49 need not, in the construction according to the present invention, be spring-closed, but a spring may be provided to assist in closing it, if desired.

The lower end 50 of the injector body 13 is screw-threaded externally and with this end an internally screw-threaded union 51 engages. This union connects the nozzle 52 with the injector body 13.

Between the nozzle 52 and the lower end of the injector body 13 is arranged a jointing ring 53 formed with a central clearance hole 54 through which the stem 49 of the needle valve passes. The jointing ring 53 has a duct 55 formed in it which is connected at its lower end to a duct, not shown, leading to a chamber in the nozzle surrounding a shoulder on the needle valve, while the upper end of the duct 55 registers with the lower end of a duct 56 formed in the body 13 of the injector. The upper end of the duct 56 opens into a cylindrical chamber 57 closed at its outer end by a screwed plug 58. Another duct 59 connects the chamber 57 with the lower part of the chamber 26.

A duct 60 is formed in the body 13 of the injector 12 and this duct connects the lower end of the chamber 36 (below the piston 48) with the chamber 29. The chamber 29, Figure 2, is connected by a duct 61 to a pipe 62 leading to the atmosphere or acting as a drain pipe and connected to a suitable receptacle. The pipe 62 has a conical end 63 which is forced into fluid-tight contact with a similarly formed end of the duct 61 on screwing up the nut 64 of which the screw-thread engages with an internal thread on the nipple 65 of the body 13 of the injector.

The plungers 23, 32 and the pistons 25, 47 and 48 are all of cylindrical form and slide in a fluid-tight manner in their correspondingly shaped respective bores or chambers 22, 26, 31, 35 and 36 and packing grooves may be formed on the plungers or pistons if desired.

The operation of the injector above described is as follows:

In Figure 1 the position of the parts corresponds to that in which the needle valve is closed and consequently no fuel is being injected into the cylinder of the internal-combustion engine with which the injector is associated. The mechanically-operated valve or distributor has opened the distributor control-pipe 41 to the pressure of the fuel supply system so that the pressure of the fuel oil in the ducts 40 and 39 and in the adjacent ends of the control-chambers 35 and 36 is that of the supply pressure in the fuel system. Accordingly the piston 48 holds the needle valve closed and the piston 47 holds the plunger 32 against the lower end of the duct 27 in the piston 25 and has sealed this duct. The pressure of the fuel oil in the inlet pipe 11 which acts on the upper end of the plunger 23 forms a fluid-tight joint between the lower end of this plunger and the upper face of the piston 25. The lower face of the piston 25 is held clear of the annular projection 30 so that pressure in the nozzle chamber is relieved through the ducts 55 and 56, chamber 57, duct 59, the part of the chamber 26 between the lower face of the piston 25 and the upper face of the constriction 28, duct 33, chamber 29, duct 61 and pipe 62. The pipe 62 leads to the atmosphere or to a drain pipe. The parts remain in the above position until the instant arrives for fuel injection to commence.

When this instant arrives the pressure of the fuel oil system is cut off from the control-pipe 41 and consequently the pressure of the oil in the control-pipe 41, duct 40, duct 39 and the adjacent ends of the control-chambers 35, 36 is relieved with the result that the pressure of the fuel supply system in pipe 11 acting on the plunger 23 forces the plunger downwards and also the piston 25, plunger 32, and piston 47, until the lower face of the piston 25 rests on and makes a fluid-tight joint with the annular projection 30 which prevents any further movement of the piston 25 and also of the annular piston 23. The pressure of the fuel oil acting in the duct 24 on the upper end of the plunger 32 forces the plunger downwards still farther with the result that the fuel oil may now pass from the duct 27 into the space enclosed within the annular projection 30 and from thence through the duct 59, chamber 57, ducts 56 and 53 to the nozzle chamber and the pressure of the fuel oil on the needle valve shoulder opens the valve so that fuel oil is injected in a finely atomised condition into the combustion chamber of the cylinder of the internal-combustion engine associated with the injector. The piston 25 when in contact with the annular projection 30 seals the duct 33 leading to the chamber 29 and to the pipe 62 which leads to the atmosphere or to a drain pipe.

When the instant arrives for injection to terminate, the distributor places the control-pipe 41, duct 40, duct 39 and control-chambers 35 and 36 in communication with the pressure fuel supply system so that the pressure in this system acts on the adjacent ends of the pistons 47 and 48. The pressure on the piston 48 closes the needle valve on its seat while the pressure of the fuel supply system is still acting thereon, and as the area of the control-piston 47 is greater than the area of the plunger 23 plus that of the duct 24, the plunger 32 closes the lower end of the duct 27 and then forces the piston 25 upwards so that the lower face of the piston 25 is moved away from the annular projection 30 upon which it previously rested. When the piston

75 on which it previously rested. When the piston

25 has been raised off the annular projection 30 the pressure in the nozzle chamber is relieved by being connected to the atmosphere or drain pipe by way of the duct 55, duct 56, chamber 57, the part of the chamber 26 beneath the lower face of the piston 25, duct 33, chamber 29, duct 61 and pipe 62.

The above cycle of operations is repeated so long as the injection system functions.

Instead of forming the various bores and chamber in the body of the injector, they may be formed in one or a number of liners and assembled with the body.

The injector as above described while operating efficiently is open to the disadvantage that in the event of a particle of carbon lodging on the needle valve seat during combustion or compression strokes of the engine cylinder associated with the injector, and of the needle valve being thereby prevented from closing properly, gases under pressure could blow fuel oil remaining in the injector ducts and passages into the atmosphere or into the drain pipe. In order to obviate the above contingency arising, the construction of the injector may be modified as illustrated diagrammatically in Figure 3.

In Figure 3 a plunger 23 has a central duct 24 and is slidably mounted fluid-tight in a bore 22 of the injector body 13. Beneath the bore 22 is arranged a guide member 70 which is fixed in an enlarged bore 11. At its upper end the guide member 70 has a chamber 72 which is of smaller diameter than the bore 22 so that a shoulder 73 is formed upon which the plunger 23 rests when in its lowest position. The plunger 32 is slidably mounted fluid-tight in a bore 74 of the guide member 70, the obturating plunger 32 being operated by a control-piston 47 slidable in a chamber 35. The control-chamber 35 is formed in a liner 75 inserted in a bore 76 of the body 13 of the injector and is interconnected by a duct 39 with a chamber 36 also formed in the liner 75. In the chamber 36 there is slidably mounted a piston 48 which is formed on the stem 49 of the needle valve of the injector. The duct 39 is connected by a duct 40 to a nipple 46 on the body 13 of the injector, the nipple being connected to the distributor pipe. Ducts 77 and 78 lead from the upper end of the chamber 35 and from the lower end of the chamber 36 to the atmosphere or to a drain pipe. The chamber 72 is connected by a duct 79 to the needle valve chamber in the nozzle. A screwed plug 80 serves as an adjustable stop to limit the outward or return movement of the plunger 23. The remaining parts of the injector are similar to that described with reference to Figures 1 and 2.

By arranging the injector as just described a sufficient increase of volumetric capacity may be given (by the increase of volume of expansion chamber 72 when the plunger 32 is lifted) to the ducts associated with the nozzle valve chamber and located within the injector so as to relieve the pressure in the fuel oil ducts without discharging the fuel to the atmosphere or to the drain pipe.

When injection commences the distributor cuts off the pressure fuel oil system from the distributor pipe connected to the injector by the nipple 46 and relieves the pressure in the ducts 49 and 39 and in the ends of the control-chambers 35 and 36 connected by the duct 39. The pressure of the fuel oil supply acting on the plunger 23 forces this plunger together with the obturating plunger 32 and the piston 47 downwards until

the plunger 22 rests on the shoulder 73. The pressure of the fuel oil acting in the duct 24 on the upper end of the plunger 32 forces this plunger still farther downwards and at the same time breaks the seal between the upper end of this plunger and the lower end of the plunger 22. The fuel oil may then freely pass by way of the chamber 72 and the duct 79 to the needle valve which it opens and so enters the cylinder of the engine associated therewith.

When injection terminates the distributor connects the adjacent ends of the control-chambers 35 and 36 through the ducts 39 and 40 and the nipple 41 to the pressure fuel supply system. The piston 48 is operated and closes the needle valve. Moreover, the control-piston 47 rises and operates the plunger 32 so that it seals the lower end of the duct 24 of the plunger 23 and raises the plunger sufficiently to supplement the capacity of the chamber 72 by that of the displacement of the plunger 23 in the bore 22 and to relieve the pressure in this chamber and also in the duct 79 and the nozzle valve chamber.

When injection recommences, the plunger 32 is pressed down by the pressure of the fuel oil supply acting on the plunger 23, and the pressure in the chamber 72 and duct 79 and nozzle chamber is increased prior to the opening of the duct 24. This tends to reduce or prevent pressure waves and fluctuations of pressure in the whole system. With this construction the needle valve will be efficiently sealed by plunger 74 even if it does not seat properly at the nozzle 52 and the fuel oil around the needle valve seat when the valve has been closed is not under pressure owing to the relief afforded by expansion of chamber 72.

It is desirable when applying the present invention in practice to include a valve so arranged that injection cannot take place until a suitable pressure of injection is generated.

The valve which is constituted by the plunger 23 coacting with the plunger or obturating-member 32 forms in itself a very useful valve which may be used in other connections, for example as a valve for the distributor itself, such for example as the distributor valve shown at 91 in Figure 5 of my United States Patents 2,291,939, granted August 4, 1942, and 2,281,302, granted April 28, 1942. In this case the plunger 32 of such a distributor valve may be cam-operated. The essential parts of the valve, when fluid-pressure-operated, are illustrated separately in diagrammatic form in Figure 4 and bear the same reference numbers as in Figure 3. In this case A represents an inlet, B an outlet to be controlled by the valve and C an inlet for pressure to control the opening and closing of the valve.

The constructions of injectors hereinbefore described are not limited to such as have piston-closing means for the fuel admission-valve which hold the needle valve 49 closed substantially solely by fluid pressure as movement of either or both of the piston-opening and piston-closing means may be assisted by spring action.

I claim:

1. A fuel-control valve for fuel-injection apparatus of internal-combustion engines and like purposes comprising a valve-body, an inlet thereto, a plunger therein having a duct extending through it from one end open to the inlet toward a seating thereon at the other end, an obturating-member movable toward the plunger to bear on the seating and thereby close the duct against

the flow of fuel through the duct, a piston face on the obturating-member exposed to inlet fuel-pressure to urge it open, an outlet passage leading from the obturating member beyond the seating on the plunger, a second piston-face on the other end of the obturating member, a control-chamber in which said second piston-face is located and an inlet from an independent supply of fluid under pressure to said chamber to close the obturating-member against said pressure, whereby seating and unseating of the obturating-member is effected to close and open the valve, the plunger and seating thereon being free to move with the obturating-member for a short distance in the closing direction after the valve is closed.

2. A fuel-control valve for fuel-injection apparatus of internal-combustion engines and like purposes comprising a valve-body, a plunger therein having a duct extending through it from a seating thereon at one end, an obturating-member movable toward the seating to obturate the duct, means to admit fluid pressure to the end of the plunger and urge the plunger and obturating-member in one direction, an abutment in the path of the plunger to interrupt its movement while allowing the movement of the obturating-member to continue under the said pressure and thus to open the valve, an outlet passage leading from the obturating member beyond the seating on the plunger, a second piston-face on the other end of the obturating member, a control-chamber in which said second piston-face is located and an inlet from an independent supply of fluid under pressure to said chamber to return the obturating-member to close the valve and to thereafter continue the movement of the obturating-member and plunger together for a short distance so as to return the parts to their initial position.

3. A valve as claimed in claim 1, wherein an expansion chamber is provided between the plunger and an annular shoulder or abutment engaging therewith, which chamber is in communication with the outlet passage and, on the relative movement which occurs between the shoulder and plunger when the plunger and obturating-member move together after the valve is closed, serves to relieve pressure in the outlet passage.

4. A valve as claimed in claim 1 wherein the movement of the plunger with the obturating-

member after the valve is closed is limited by an adjustable stop for the purpose described.

5. A valve comprising in combination a valve body having a cylindrical bore near one end thereof, an inlet at the end of the valve body to the cylindrical bore, a plunger slidable in the bore and pierced with a longitudinal passageway, a seating on the end of the plunger remote from the inlet, the plunger being at liberty to execute limited endwise sliding movement in the bore, a smaller bore in the valve body beyond the plunger and coaxial therewith, an obturating member slidable in said bore and capable of sealing the passageway through the plunger by abutting upon the seating, a chamber surrounding the junction of the obturating member and the plunger, an outlet passage from the said chamber, an additional valve member movable to open and close the outlet passage and control means for closing the second valve and for simultaneously closing the obturating member upon the seating and forcing back the plunger to relieve pressure in the outlet passage between the chamber and the additional valve member.

6. A valve comprising in combination a valve body having a cylindrical bore near one end thereof, an inlet at the end of the valve body to the cylindrical bore, a plunger slidable in the bore and pierced with a longitudinal passageway, a seating on the end of the plunger remote from the inlet, the plunger being at liberty to execute limited endwise sliding movement in the bore, a smaller bore in the valve body beyond the plunger and coaxial therewith, an obturating member slidable in said bore and capable of sealing the passageway through the plunger by abutting upon the seating, a chamber surrounding the junction of the obturating member and the plunger, an outlet passage from the said chamber, an additional valve member movable to open and close the outlet passage, a control chamber in the valve body, a control piston upon the obturating member open to said control chamber, a second control piston upon the said additional valve member, also open to said control chamber and an inlet to the valve body for application of fluid pressure to said control chamber to close the additional valve and to operate the obturating member to close it upon the seating of the plunger.

GEORGE AMERY.
